UNITED STATES PATENT OFFICE.

HAMILTON CLAYTON BOGGS, OF DECATUR, ALABAMA.

INFLATABLE TIRE.

1,182,871.

Specification of Letters Patent.

Patented May 9, 1916.

Continuation of application Serial No. 875,710, filed December 5, 1914. This application filed March 27, 1916. Serial No. 87,063.

To all whom it may concern:

Be it known that I, HAMILTON CLAYTON BOGGS, a citizen of the United States, residing at Decatur, in the county of Morgan and State of Alabama, have invented 5 new and useful Improvements in Inflatable Tires, of which the following is a specification.

This invention has relation to certain improvements in inflatable tires and more particularly to the inner tubes therefor of the style the material of which is under compression, instead of in tension, when the tube is incased and inflated.

10 Important objects of the invention are to provide a thoroughly practicable inner tube of the style stated, and, moreover, one which when deflated will avoid the rupture due to rim cutting. In accordance with these 15 objects, the invention provides an inner tube having a structure and shape such that it will have a fixed formation when deflated, this formation being such that: (1) the tube may be placed in the casing without 20 danger of creasing or pinching, (2) in which the material is very effectively compressed and the compression will be substantially equalized throughout the tread portion and the sides adjacent to the tread portion, and 25 (3) in which, in the event of the deflation of the tube, and when the tube is under load, the material thereof will fold in a peculiar manner and present several thicknesses of material between the tread portion 30 of the casing and that portion of the casing which is engaged by the edge of the rim of the wheel, thereby preventing rim cutting of the casing or tube.

In the accompanying drawings, I have 35 exemplified certain particular forms of the invention adapted to carry into practice the several purposes in view, but it will be understood that these forms are merely exemplary and that the invention may be variously embodied without departing from its spirit, as defined by the appended claims.

In the accompanying drawings, illustrating preferred embodiments of the invention, and wherein like characters of reference 40 denote corresponding parts in the several views:—Figure 1 is a cross sectional view through one form of casing and inner tube, the tube being shown in deflated condition and not under load; Fig. 2 is a similar view, 45 showing the shape of the inner tube when

inflated; Fig. 3 is a cross sectional view through one style of rim and casing, having my improved inner tube therein, the tube being shown in deflated condition and not under load; Fig. 4 is a like view illustrating the tube when inflated; and Fig. 5 is a like view through a section of tube, casing and rim, showing the condition of the tube and its correlation with the rim and casing, in that part of the tire which is under load and when the tube is deflated.

A in Figs. 1 and 2, and A' in Figs. 3, 4 and 5, designate different forms of tire casings of the clincher type, and B in Figs. 3, 4 and 5 designates a clincher rim for engagement therewith. While both forms show casings of the clincher type, it should be understood that my invention is not restricted to this type, or indeed to any particular type or construction of either casing or rim, as any approved construction and type may be employed without departing from the spirit of the invention or the scope of the appended claims.

The inner tube, marked C in Figs. 1 and 2 and C' in Figs. 3, 4 and 5, constitutes the important part of the present invention, and, as clearly shown, is molded or otherwise suitably formed of resilient compressible material, impermeable to the passage of air, soft rubber being preferred, and is made thick and heavy so that it will maintain a fixed formation when deflated, effectively close a puncture when its material is under compression, and form a most effective cushion when deflated and under load. The fixed formation referred to includes a few wide and pronounced annular depressions in the tread and sides, the tread depressions being separated from the side depressions by bearing portions, and between the side depressions are other bearing portions, the latter bearing portions conforming to the casing and rim with which the tube is to be used.

More particularly, as shown in Figs. 3, 4 and 5 of the accompanying drawings, the inner tube C' is formed with continuous annular depressions 1 and 2 in its opposite sides, and with a continuous annular depression 3 in its tread. The depression 3 preferably extends substantially across the entire tread portion of the tube and is separated from the side depressions 1 and 2 by bearing surfaces 4 and 5, which pref-

erably form annular outwardly-projecting looped portions, for contact with the inner wall of the casing. The depressions 1 and 2 are separated from each other, at the rim side of the tire by bearing portions which include parts 6 and 7, which are oppositely inclined and lie against the casing, at the rim side of the latter substantially throughout their length, and are connected with each other by the portion 8, which portion 8, in the form exemplified in Figs. 3, 4 and 5, engages the rim A. The tube C illustrated in Figs. 1 and 2 differs from the tube C' only in that its bearing portions at the rim side are outwardly curved to conform to the contiguous portion of the casing, providing parts 6^a, 7^a and 8^a which respectively correspond to the parts 6, 7 and 8 of the tube C; the part 8^a, however, lying in contact with the casing.

The side depressions marked 1 and 2 on both forms preferably extend from a place above to a place below the center of the tire, the angular disposition of the material at the junction of the depressed portions 1 and 2 and bearing portions 6 and 7 of the tube C' or 6^a and 7^a of the tube C forming what may be regarded as shoulders 9 and 10, respectively. The bearing surface formed by the portions 6, 7 and 8, or 6^a, 7^a and 8^a, intermediate the lower margins of the side depressions 1 and 2, is of a width materially in excess of the width of the bearing or contacting surfaces 4 and 5, and the bearing portions 6 and 7, or 6^a and 7^a extend to points which are slightly beyond the edges of the rim, that is to say, slightly beyond the point at which the rim-cutting usually occurs. The several annular depressions or inbows 1, 2 and 3 are preferably equi-distantly spaced. In practice, the tube is of such size with relation to that of the bore of the casing that when inflated its material will be under compression, and it will be understood that when the inflation medium is admitted to the inner tube the material forming the depressions 1, 2 and 3 will be forced outwardly and lie smoothly against the contiguous portions of the inner wall of the casing. It will be noted that the bearing portions 4 and 5 are not connected with each other by any extraneous element or member of a non-expansile or incompressible nature and hence are free to move toward or away from each other while the tube is being inflated, except as restrained by frictional contact with the casing. It will also be noted that the several bearing portions 4, 5, 6 and 7, or 4, 5, 6^a and 7^a are constantly in contact with the casing while the tube is being inflated and after it is deflated.

From the foregoing it will be apparent that a tire constructed as described not only has the important advantage of effectually

closing any punctures which occur in either the tread or sides of the inner tube, but, furthermore, possesses all of the resiliency of an unarmored tire, and that the tube may be readily inserted in a casing without any danger of its being improperly folded, creased or pinched. Moreover, in the event of the deflation of the tube from any cause, such as a leaky valve, for example, while the tube is under load, the tube will fold in a novel and peculiar manner and present several thicknesses of material between the tread portion of the casing and that portion of the casing engaged by the edge of the rim of the wheel, thereby effectually protecting the casing against rim cutting and being itself effectually protected against cuts at the portion adjacent to the rim. All these several important advantages are secured in a simple, single and unitary structure which may be readily molded. These advantages will be best appreciated by an understanding of the conditions met with in the use of automobile tires. A frequent cause of injury to the inner tube of automobile tires arises from the fact that these inner tubes are sometimes creased or folded when they are placed within the casing, or some part thereof are pinched between the lower edge of the casing and the rim of the wheel when the tire is being placed upon the wheel. If a tire is used when its tube is thus pinched, creased or folded, a rupture soon follows.

It will be evident that a tube having the construction herein disclosed may be placed within a casing without the exercise of any special care on the part of the person who is applying the tube.

Another frequent cause of injury to the outer casing of automobile tires is due to the fact that when the casing becomes completely collapsed and the edge of the rim of the wheel is permitted to run thereupon "rim cutting" of the casing results and the walls and fabric of the casing are so ruptured or weakened that blow-outs soon follow, the inner tube being itself liable to injury from the same conditions.

With the tube herein described; if the tire becomes deflated when under load, the side depressions or inbows 1 and 2 fold inwardly and the tread inbow 3 straightens to permit the bearing surfaces 4 and 5 to overlap the shoulders 9 and 10, as shown in Fig. 5, and thereby afford a cushion which will prevent rupture of the casing or tube.

It will be apparent that the invention is susceptible of some change and modification without substantial departure from the principle and spirit thereof and for this reason I do not wish to be understood as limiting myself to the precise arrangement and formation of the several parts herein shown, in carrying the invention into practice.

The present application is filed as a substitute for and continuation of my application for Letters Patent filed December 5, 1914, Serial No. 875,710, allowed March 3, 5 1916.

Having now described the invention, what I believe to be new and desire to secure by Letters Patent, and what I therefore claim is:

- 10 1. In combination with a tire casing, an inner tube, said tube being molded and having a substantially fixed formation in cross section when deflated, the tube when deflated having a continuous annular depression in 15 its tread portion and continuous annular depressions in its opposite sides, substantially equidistantly spaced relative to the depression in the tread portion, the tube being provided intermediate the depressions with 20 bearing surfaces adapted for substantially constant contact with the tire casing, the bearing surface between the inner marginal portions of the depressions in the side faces of the tube being of a width materially in 25 excess of the widths of the two bearing surfaces afforded between the depression in the tread and the depressions in the sides of the tubes, said annular depressions of the tube permitting a reduction of the maximum 30 diameter of the tube when said tube is deflated, the depressed portions of the tube being compressed when the tube is inflated after being placed within the casing.

2. An inner tube for tires, said tube being 35 molded and having a substantially fixed formation in cross section when deflated, said tube when deflated having a continuous annular depression in its tread portion and continuous annular depressions in its opposite 40 sides substantially equidistantly spaced relative to the depression in the tread of the tube, said tube being provided intermediate the depressions with bearing surfaces adapted for substantially constant contact with 45 the tire casing, the bearing surface between the inner marginal portions of the depressions in the side faces of the tube being of a width materially in excess of the widths of the two bearing surfaces afforded between 50 the depression in the tread of the tube and the depressions in the side faces of the tube, the material of the depressed portions of the tube being compressed when the tube is inflated after being placed within the casing.

- 55 3. An inflatable pneumatic inner tube for

tires made of compressible material and molded to have a fixed formation when deflated, the said formation including an annular tread inbow and annular side inbows all of said inbows being wide and pronounced, the tread inbow being separated from the side inbows by bearing projections, said projections being free to move toward and from each other, the tread inbow extending across substantially the entire tread portion of the tube and the tube having a cross sectional periphery greater than the internal circumference of the casing in which it is to be used, when in its deflated condition, the inner side of the tube having oppositely inclined side walls which are connected with the bearing projections by the side inbows, said walls being of such shape as to be in contact with an inclosing casing substantially throughout their length and serving to anchor the tube with relation to the casing.

4. A tire comprising a casing and an inflatable pneumatic inner tube therefor made of compressible material and molded to have a fixed formation when deflated, the said formation including a wide and pronounced annular tread inbow and wide and pronounced opposite, annular side inbows, said tread and side inbows being spaced from each other by bearing projections that are free to move toward and from each other, that portion of the tube that is disposed toward the rim side of the casing comprising outwardly inclined side walls which extend outwardly beyond that portion of the casing at which the latter is engaged by the rim, when the tire is being run in a deflated condition, the juncture of said inclined walls with the side inbows forming shoulders, the parts being so proportioned and arranged that when the tube is deflated and under load the side inbows fold inwardly and the tread inbow straightens to permit the bearing projections to overlap said shoulders to thereby present several thicknesses of material between the tread portion of the casing and those portions of the casing engaged by the edges of the rim, to thereby prevent rim cutting of the casing or tube.

In testimony wherof I have hereunto set my hand, at Decatur, in the county of Morgan and State of Alabama, this 24th day of March, 1916.

HAMILTON CLAYTON BOGGS.
